UNITED STATES PATENT OFFICE.

ROBERT E. BEAUBIEN, OF CHICAGO, ILLINOIS.

HAND-DRILL.

1,362,582.

Specification of Letters Patent. Patented Dec. 14, 1920.

Application filed April 18, 1919. Serial No. 291,008.

To all whom it may concern:

Be it known that I, ROBERT E. BEAUBIEN, citizen of the United States, residing at Chicago, Illinois, have invented certain new

5 and useful Improvements in Hand-Drills; and I do hereby declare the following to be a full, clear, and exact description of the invention, such as will enable others skilled in the art to which it appertains to make 10 and use the same.

My invention relates to hand drills, its general objects being to provide an unusually simple and easily manufactured drill including a geared operating mechanism, to 15 provide convenient means for storing the needed drill points, and to secure a stiff frame while employing light metal. More particularly, my invention aims to provide a geared hand drill so designed that most 20 of its parts can be manufactured by simple punch press operations; to provide simple and effective means for stiffening the frame; to utilize some of the stiffening means for storing drill points and for maintaining 25 the gearing intermeshed; and to accomplish the further and more detailed objects appearing from the following specification and from the accompanying drawings, in which—

30 Figure 1 is an elevation of the preferred embodiment of my invention.

Fig. 2 is an enlarged transverse section through the same looking upward from the bottom of the pinion in Fig. 1.

35 Fig. 3 is an enlarged and fragmentary view of a portion of the gear and of the pinion teeth engaged therewith.

Fig. 4 is an enlarged longitudinal section through the handle and the drill-case, taken 40 centrally of Fig. 1.

Fig. 5 is an enlarged transverse section through the handle and drill-case, taken along the correspondingly numbered line in Fig. 1.

45 Fig. 6 is an enlarged and fragmentary section through another embodiment of my invention, namely one in which the metal parts are secured to each other by two rivets and in which the cross-bar in the forward 50 loop is omitted.

Fig. 7 is an elevation of a hand drill similar to that of Fig. 1, but employing a

differently made gear and constructed without the drill case.

Fig. 8 is a side elevation of the embodiment of Fig. 7. 55

Fig. 9 is an enlarged and central longitudinal section through a part of the embodiment of Fig. 7.

Fig 10 is an enlarged perspective view of 60 the cross-bar 4 as shown in the embodiments of Figs. 1 and 7.

Fig. 11 is an enlarged perspective view 65 of a drill point suitable for use with my invention.

Fig. 12 is a perspective view of the body of the drill case which stiffens the handle, showing this before the handle loop is clamped around it.

In the embodiment of Figs. 1 and 7, the 70 frame of my hand drill is constructed of two pieces of flat strip steel, of which the shorter forms a cross-bar across the forward loop of the longer strip. This longer strip is bent substantially into a pair of loops 75 connected by approximately parallel parts, the rear loop being desirably rounded to afford a handle 1. The forward loop 2 desirably has its extreme forward end flattened transversely of the axis of the frame 80 of my appliance and perforated to afford the forward bearing for the shank 3 of a drill chuck. This shank 3 also extends through a central perforation in a cross bar 4 which spans the loop 2. At the rear end 85 of this loop the two strip portions are dished out so as to form opposed recesses housing a steel ball 5 which forms a thrust bearing for the lower end of the drill chuck shank 3. This lower end desirably is smaller in 90 diameter than the main portion of the said shank and is knurled during its manufacture, after which this contracted end is pressed through the bore of a pinion 6, thus firmly securing the pinion to the said shank, 95 in doing which the knurling on the shank produces corresponding formations in the bore of the gear so as to prevent a rotation of the latter upon the shank.

Back of the ball 5, the two shank portions 100 of the frame are bowed out into opposed arch formations 7, thereby affording a bearing for a shaft 8 carrying a disk 9. This disk has near its periphery a series of per-

forations spaced to match the spacing of the teeth on the pinion 6, with which teeth the walls of the perforations are intermeshed, so that the disk forms a driving gear 5 for rapidly rotating the pinion. Motion is imparted to the disk for this purpose through a crank handle 10 fastened to the disk, and the disk is prevented from being bent out of its intermeshed relation 10 with the pinion by a finger 11 on the cross-bar 4, as shown in Figs. 2 and 8.

At its forward end, the rotatable shank 3 is provided with suitable means for holding and gripping drill bits. For example, the 15 tip of the shank may have longitudinal slots extending in two relatively transverse directions, thus forming four fingers 12, which are desirably tapered at their free ends. Then each of the drills 13 may have a shank 20 of a size fitting the bore of the forward end of the shank 3, this shank of the drill being flattened at its rear end to enter the slot between the fingers 12, whereby these fingers will prevent the drill from rotating with 25 respect to the shank 3. Thus arranged, the drill may be clamped in position by a shell 14 threaded upon the shank 3 and tapered to correspond to the tips of the fingers 12, so that the screwing of this shell 14 on the 30 shank 3 will flex the fingers 12 and cause the latter to grip the drill bit.

To simplify the construction, the frame of my appliance is desirably formed of a single strip of steel having its ends overlapped 35 near the shaft 7, as shown in Fig. 1, so that a single rivet 15, together with the staking over of the ends of the cross-bar 4, will hold the strip in its desired form for affording proper bearings for the shaft 8 and the ball 5. In this manner, I am able to secure 40 a rigid construction while using light material both for the frame and for the rotat- ing disk; and by suitably shaping the re- cesses which house the ball 5, I can provide 45 for an adequate thrust bearing without re- quiring great accuracy in the assembling of the parts. That is to say, the chuck shank 3 may have some freedom of motion longi- tudinally, thereby facilitating the assem- 50 bling, as the steel ball 5 will limit its rear- ward movement, while its forward move- ment will be limited through the intermesh- ing of the pinion teeth with the perforations in the disk 9.

55 In assembling the tool as above described, there may be little variations in the effective diameter of the gear 9, and this diameter will be further varied by the wear on the thrust ball and on the end of the shank 3. 60 To allow for this, I desirably employ perforations in the disk 9 extending radially of the latter for a greater distance than the width of the teeth of the pinion. For example, instead of entirely punching out the 65 pieces in making the perforations, I may

form opposed prongs as shown in Figs. 1, 2 and 3, these being wider than the thickness of the pinion and shaped for a rolling contact with the pinion teeth.

To secure the desirable rigidity in the frame while constructing the latter of light strip steel, I desirably stiffen the loop which constitutes the handle, after the manner shown in Figs. 1, 4 and 5. For this purpose, I stamp a box 16 out of thin metal with 70 sides shorter than the width of the strip steel, the box being tapering and rounded at its larger end. Then I insert this box in the handle loop before inserting the rivet 15, thus clamping the box within this loop. 80 To prevent the box from being slid out of the handle, I desirably concave the handle-forming part of the strip as shown in Figs. 4 and 5, so that the resulting loop will overhang the edges of the box and will effec- 85 tively retain the latter, while the box in turn stiffens the handle. Then I close the box with a telescoping cover 17 and use this box for storing drill points 13 of various sizes. However, while I have pictured and described the tool of my invention as including a certain cheaply constructed form of chuck, I do not wish to be limited to this or other details of the construction and arrangement here disclosed, it being obvious 90 that the same might be varied in many ways without departing from the spirit of the ap- pended claims. For example, Figs. 7 and 8 show an embodiment in which the handle- stiffening drill-case is omitted and in which 100 the teeth-engaging apertures in the disk 9 are simple round holes. Fig. 6 shows a con- struction in which the cross-bar is omitted and an added rivet 14 is used between the gear and the thrust ball, while the rear end 105 of the chuck shank is journaled in the re- cesses housing the thrust ball, these recesses being correspondingly lengthened.

I claim as my invention:

1. In a hand drill, a frame formed from 110 a single strip of metal and comprising a handle loop, a forward loop, and a shank portion connecting the two loops and con- sisting of strip parts overlapped longitudinally of the frame; the forward loop hav- 115 ing a perforation axial of the frame; a ro- tatable shank extending through the said per- foration axially of the frame to the juncture of the forward loop with the said shank portion of the frame and journaled both in 120 the forward loop and at the said juncture, and driving means carried by the shank por- tion of the frame for rotating the said rotat- able shank.

2. An appliance as per claim 1, in combi- 125 nation with a perforated cross-bar spanning the forward loop, the rotatable shank ex- tends through the perforation in the cross bar and being also journaled therein.

3. In a hand drill, a frame having as its 130

forward portion a loop equipped at its forward end with a perforation and having its sides overlapping longitudinally of the frame, a cross-bar spanning the loop and having a perforation in alignment with the aforesaid perforation, a chuck shank extending through the said perforation, a pinion fast on the shank back of the cross-bar, a thrust bearing for the shank, and driving means for rotating the pinion.

4. In a hand drill, a frame having as its forward portion a loop formed by doubling a strip of metal on itself, and perforated at its forward end; a chuck shank rotatably mounted in the said loop and extending forwardly through the said perforation, the two portions of the doubled strip having opposed recess formations at the rear end of the loop; and a single ball housed jointly by the recess formations and engaging the rear end of the chuck shank to form a thrust bearing for the latter.

5. A hand drill as per claim 3, in which the thrust bearing consists of opposed recess formations at the rear end of the loop and a single ball socketed in the said recess formations.

6. In a hand drill, a frame having as its forward portion a loop equipped at its forward end with a perforation, and having its sides overlapping longitudinally of the frame, a cross-bar spanning the loop and having a perforation in alignment with the aforesaid perforation, a chuck shank extending through the said perforation, a pinion fast on the shank back of the cross-bar, a thrust bearing for the shank, and driving means for rotating the pinion, the cross-bar having a finger overhanging the driving means to maintain the latter in operative relation to the pinion.

7. In a hand drill, a frame having its main member formed of a single strip of metal doubled twice on itself to form two loops joined by longitudinally overlapping portions, the rear loop forming a handle, and the overlapping portions being secured to each other adjacent to the handle and having opposed arch formations forwardly of the said securing point; the forward loop having a perforation axial of the frame; a shaft journaled in the said opposed arch formations and in the said perforation and extending axially of the frame; a shaft journaled in the frame between the said securing point and the said arch formations and extending transversely of the frame, and intermeshed gears fast respectively on the said shaft and shank.

8. In a hand drill, a frame consisting of a single strip of metal doubled upon itself to form two loops connected by a shank, and a drill case housed by one of the said loops and serving to stiffen this loop.

9. In an appliance of the class described, a frame formed of strip metal and including a loop having a perforation at its forward end coaxially of the frame and having its opposite side portions extended in overlapped relation rearwardly of the loop and coaxially of the frame, the said side portions having opposed recess formations at the juncture of their said overlapped parts with the said loop; a single thrust ball housed jointly by the said recesses, a cross-bar spanning the loop and having a perforation coaxial with the frame, and a rotatable shank journaled both in the perforation at the forward end of the loop and in the perforation of the cross-bar and bearing at its rear end against the thrust ball.

10. An appliance as per claim 9, in combination with a pinion fast upon the rotatable shank, a gear rotatably mounted on the frame back of the thrust ball and meshing with the said pinion, and means on the cross-bar for holding the gear intermeshed with the pinion.

11. In an appliance of the class described, a frame consisting of a single strip of metal bent to form two loops connected by a shank extending longitudinally of the frame along the axis of both loops, the shank being composed of two overlapping strip portions having opposed recess formations at their juncture with the forward loop and having a pair of opposed substantially semi-cylindrical recess formations at a point back of the aforesaid formations; means for securing the overlapped strip portions to each other adjacent to the last named recess formations; a cross-bar spanning the forward loop and secured at both ends of the loop and having a perforation axial of the frame, the forward loop also having at its forward end a perforation coaxial with the frame; a rotatable shank journaled in the said perforations in the cross-bar and in the forward end of the loop, a transverse shaft journaled in the said semi-cylindrical recess formations, a gear carried by the transverse shaft, and a pinion fast upon the rotatable shank and intermeshed with the said gear.

12. In an appliance of the class described, a frame formed from a single strip of metal bent flatwise into two loops connected by overlapping strip portions extending longitudinally of the frame and substantially coaxial with both of the loops, one of the loops having its strip portions inwardly convexed, and stiffening means narrower than the strip and housed by the last named loop and retained in position by the said convexing.

13. In a hand drill, a frame formed from a single strip of metal bent flatwise to form two loops and a double thickness shank connecting the same, a chuck shank journaled in the forward loop and coaxial with both

loops and with the aforesaid shank, and a drill case clamped within the rear loop and stiffening the same.

14. In a hand drill, a frame formed from a single strip of metal bent flatwise to form two loops and a double thickness shank connecting the same, a chuck shank journaled in the forward loop and coaxial with both

loops and with the aforesaid shank, a shaft journaled between the two thicknesses of the shank and extending transversely of the general plane of the loops, a pinion on the chuck shank, and driving means on the shaft intermeshed with the pinion.

Signed at Chicago, April 14th, 1919.

ROBERT E. BEAUBIEN.
